UNITED STATES PATENT OFFICE.

BENJAMIN SAINSBURY WOODS AND SAMUEL LEWIS, OF TRANScona, MANITOBA,
CANADA.

STOCK-RAIL.

1,177,670.

Specification of Letters Patent.

Patented Apr. 4, 1916.

Application filed September 8, 1914 Serial No. 860,625.

To all whom it may concern:

Be it known that we, BENJAMIN SAINSBURY Woods and SAMUEL LEWIS, both of the town of Transcona, in the Province of 5 Manitoba, Canada, have invented certain new and useful Improvements in Stock-Rails, of which the following is the specification.

The invention relates to improvements in 10 stock rails especially stock rails used on railways at switches and the object of the invention is to provide an improved form of stock rail which will receive and protect the advanced end of the switch rail 15 thereby preventing the switch point from becoming damaged, broken or otherwise injured by the constant passage of trains as invariably occurs under present conditions.

With the above object in view the invention 20 consists essentially in the arrangement and construction of parts hereinafter more particularly described and later pointed out in the appended claim, reference being had to the accompanying drawing in which—

25 Figure 1 represents a plan view of a portion of a main line and the switch track with our invention applied. Fig. 2 represents a horizontal sectional view through the track, the section being taken in the 30 plane denoted by the line X—X' Fig. 1. Fig. 3 represents an enlarged detailed face view of a portion of the stock rail. Fig. 4 represents an enlarged detailed vertical sectional view through the stock rail and 35 switch rail, the section being taken in the plane denoted by the line Y—Y' Fig. 2. Fig. 5 represents an enlarged detailed vertical sectional view through the stock rail and switch rail, the section being taken in 40 the plane denoted by the line Z—Z' Fig. 2. Fig. 6 represents an enlarged detailed vertical sectional view through the stock rail and switch rail, the section being taken in the plane denoted by the line T—T' Fig. 2. 45 Fig. 7 represents an enlarged detailed vertical sectional view through the stock rail and switch rail, the section being taken in the plane denoted by the line P—P' Fig. 2.

In the drawing like characters of reference indicate corresponding parts in each figure.

1 and 2 represent stock rails mounted in

the usual way on the ties or sleepers 3 to which they are secured permanently by the customary spikes 4.

5 and 6 represent switch rails of ordinary construction having their advancing ends shiftably mounted on the ties and connected to each other by tie bars 7 and 8, the arrangement being such that by the manipulation of the arm 9 associated with the bar 7, the advancing ends of the switch rails can be shifted in respect to the main line rails to effect the passage of the train through on the main line or onto the switch track as 65 wished.

Our invention relates in no way to the construction or manipulation of the switch rails or in the manner in which they are shifted, residing wholly in the construction 70 of the stock rail.

According to our invention the head of the stock rail is cut or channeled on the switch rail side as indicated at 10 in a special manner to receive the advancing end 75 of the switch rail. Immediately opposite the forward or advancing end of the switch rail, the channel cut in the head is deepest as shown in Fig. 4 the depth of the channel being sufficient to receive wholly the forward end of the switch rail when the said switch rail is thrown over against the stock rail. At this particular point it is also to be noticed that the channel so cut in the stock rail provides an overhanging portion 80 11 which completely covers the advanced end of the switch rail. The channel formed in the head of the stock rail gradually decreases in depth and increases in width from the point wherein the section shown 85 in Fig. 4 is taken, to the point where the section shown in Fig. 7 appears, at which latter point the channel entirely disappears, the rail having at this latter location its natural contour. In actual practice the distance between these two points may be possibly eighteen inches or, in other words, it is equal to the distance which is customarily understood as the length of the switch rail point.

100 We might here remark that the advanced end of the switch rail tapers both at the sides and at the top, having the greater cross sectional area at some distance back from

the point and gradually tapering and decreasing in cross sectional area from this larger section to the front end.

According to our invention, as obvious from the description hereinbefore given, the stock rail is simply cut to accommodate a portion of the forward or advanced end of the switch rail as it will be seen from observing the various sections appearing in Figs. 4, 5, 6 and 7 of the drawing that in Fig. 4 the channel in the head receives fully the forward end of the switch rail while in the other sectional views the switch rail is gradually increasing in cross section while the channel is gradually decreasing in depth and increasing in width.

With a stock rail of the above nature inserted at a switch the hammering of the wheels of a passing train on the switch rail point is minimized to a marked extent as it will be seen the point of the switch rail is fully covered by the head of the stock rail

at the point where the wheels are directed on the switch rail.

What we claim as our invention is;— 25

In combination, a stock rail having the head thereof cut to present a channel on the inside which gradually decreases in depth and increases in width in passing lengthwise of the rail, and a stock shiftable 30 flat sided switch rail tapered both transversely and longitudinally, the point of said switch rail being adapted to fit into said channel whereby the outer edge thereof is flush with the stock rail so that the wheel of a 35 passing train will be gradually forced laterally without riding the switch rail.

Signed at Winnipeg, this 8th day of August 1914.

BENJAMIN SAINSBURY WOODS.
SAMUEL LEWIS.
